TYPEWRITING MACHINE

Charles Walker and William A. Gabrielson, Syracuse, N. Y., assignors to L. C. Smith & Corona Typewriters, Inc., Syracuse, N. Y., a corporation of New York

Application July 10, 1940, Serial No. 344,766

14 Claims. (Cl. 197—63)

The invention relates to improvements in typewriting machines, and more particularly to margin regulating mechanism for controlling the limits of travel of the platen carriage in such machines.

An object of the invention is to provide an improved margin regulating mechanism wherein the right and left hand margin stops may be independently adjusted either by direct hand manipulation of the stop or stops or indirectly by hand-controlled stop-setting means selectively operable upon the stops.

Other objects of the invention are to provide improved margin stops for use with hand-controlled stop-setting means, and to provide hand-controlled margin stop setting means of improved construction and efficiency.

A further object of the invention is to provide efficient margin stop setting mechanism of light and inexpensive construction for machines having so-called "wide" carriages as well as for machines having carriages of standard width.

To the foregoing and other ends which will hereinafter appear, the invention consists of the improved devices, features of construction, and arrangements and combinations of parts herein-after particularly described and particularly pointed out in the appended claims.

The improvements have been illustrated as embodied in preferred forms in two known L. C. Smith typewriting machines having respectively a platen carriage of standard width and a wide platen carriage of approximately double the standard carriage width.

In the drawings:

Fig. 1 is a fragmentary front view of the machine having the carriage of standard width, certain known parts being broken away and others omitted for clarity of illustration of the improvements, the margin regulating means being shown in a normal position for use;

Fig. 2 is a sectional view on the line 2—2 of Fig. 1;

Fig. 3 is a detail front view illustrating part of the margin stop setting means located adjacent the right hand end of the carriage;

Fig. 4 is a sectional view on the line 4—4 of Fig. 3;

Fig. 5 is a fragmentary top plan view of the margin regulating mechanism;

Fig. 6 is a rear view thereof;

Fig. 7 is a detail sectional view on the line 7—7 of Fig. 6;

Fig. 8 is a detail sectional view on the line 8—8 of Fig. 9;

Fig. 9 is a detail sectional view on the line 9—9 of Fig. 6, but showing the right hand margin stop unlatched from the margin stop bar for setting travel of the stop along the bar;

5 Fig. 10 is a sectional view on the line 10—10 of Fig. 6 showing the left hand margin stop unlatched for setting travel along the stop bar;

Figs. 11 and 12 are views similar to Fig. 4 showing respectively the control handle of the stop setting mechanism rocked to unlatch the right hand margin stop and rocked to unlatch the left hand margin stop;

Fig. 13 is a view similar to Fig. 1 showing a modified form of the invention embodied in a wide carriage machine;

15 Fig. 14 is a sectional view on the line 14—14 of Fig. 13; and

Fig. 15 is a detail perspective view showing certain parts of the right hand margin stop separated from each other, said parts being similar to corresponding parts of the left hand stop except where differences are pointed out herein-after in the description.

The improvements are shown embodied in an 25 L. C. Smith machine constructed (except as modified by the present invention) substantially as shown and described in patent to Carl Gabrielson, No. 1,933,550, granted November 7, 1933. Said machine has mounted on the usual main frame

30 10 thereof the usual platen carriage 11 which travels transversely of the machine and is controlled for letter space feeding from right to left by the usual escapement device, the carriage carrying the usual feed rack 12 through which it is fed step by step in letter space direction and held in different letter space positions by the escapement device. The usual platen roller 13 is journaled on the carriage in the usual manner for rotation about an axis 14.

35 40 The carriage also has held thereto the usual letter space scale 15, and there is held to the main frame the usual indicator device 16 having a graduation or index mark 16^a for coaction with the graduations of scale 15 to indicate the letter

45 45 space position occupied by the carriage. The usual frame stop means or counter stop means for the margin stops on the carriage is also mounted as usual on the main frame 10 substantially midway between the sides of the machine,

50 55 said counter stop means comprising the usual abutment members 17 and 18 for coaction respectively with the left hand margin stop and the right hand margin stop on the carriage. The usual toothed or dented margin stop bar 19 is adjustably held by screws 20 to the usual pair of

brackets 21, which brackets are held to the carriage as usual by screws 22. The margin bar is provided along its lower edge with the usual row of uniformly spaced teeth 19^a for latching of the margin stops to the bar in different letter space positions.

The machine is also preferably provided with the usual margin releasing means described and shown in said patent, and the usual terminal or final stops disclosed in said patent are preferably mounted on the bar 19 of the improved machine as indicated at 23 and 24 for carriage stopping coaction of stop 23 with a stop shoulder 25 on the main frame and for carriage stopping coaction of stop 24 with abutment 18, as is explained in said patent.

The usual paper table or apron 26 is held to the carriage through table carried brackets 27 clamped to the carriage as usual by the screws 22, said table consisting as usual of two sections hingedly connected at 28 for swinging forward of the upper table section to uncover the margin stops and stop bar.

The improvements will now be described, the embodiment of Figs. 1 to 12 being first described, and then the modified embodiment of Figs. 13 and 14.

Rigidly held to the brackets 21 on the carriage as by screws 29 are a pair of bearing brackets 30 for an oppositely rockable margin stop unlatching bar 31. This bar is formed of sheet metal and is of inverted U-shape or channel form in cross section, said bar extending transversely of the machine along the carriage above the stop bar 19 with its side flanges or walls pendent and preferably flaring outward and downward away from each other as shown. Rigidly held in the channel of bar 31 at each end of the bar (as by rivets 32) are two trunnion blocks 33 each formed with a reduced trunnion 33^a journaled in a bearing hole in the adjacent bracket 30 to support bar 31 for oscillation about an axis parallel to the stop bar 19.

To limit the extent of rocking movement of the unlatching bar 31 in both directions from the normal idle position thereof shown in Figs. 1 to 7 to the respective stop unlatching positions thereof one of which is shown in Figs. 9 and 11 and the other in Figs. 10 and 12, two sheet metal stop arms 34 and 35 are provided for stopping engagement of arm 34 with the front face of margin stop bar 19 and stopping engagement of arm 35 with the rear face of bar 19 near the right hand end of said bar 19. These stop arms 34 and 35 are rigidly held at their upper ends to the right hand trunnion block 33 respectively at the front and rear faces of said block by suitable means such as rivets 36 as indicated in Fig. 3. The lower ends of the stop arms 34 and 35 are spaced from the stop bar 19 in the idle position of the bar, and said stop arms are permanently bendable fore and aft of the machine to adjust the normal spacing of the lower end of each arm from the adjacent face of bar 19.

A sheet metal handle arm 37 formed integrally with the upper riveted end of stop arm 34 is provided for rocking the unlatching bar 31. The handle carrying arm is provided at its forward end with a suitable finger piece or handle 37^b and projects forwardly beyond the paper table 26 adjacent the right hand edge of the paper table for convenient manipulation from the front of the machine. Adjacent its rear anchored end this handle arm is provided with a flat-faced lateral offset portion 37^a extending transversely of the

machine. An upstanding single leaf spring 38 which extends up past the offset 37^a is rigidly anchored at its lower end to the front of the right hand bracket 21, as by a screw 39, with said spring 5 above its anchorage spaced forwardly from the bracket 21 and normally engaged adjacent its free upper end flatwise against the flat rear face of offset portion 37^a of the handle arm 37 to normally restore to, and yieldingly hold the unlatching bar and handle arm in, the intermediate idle position shown in Figs. 1 to 7. Suitable indicia such as indicated at 40 in Fig. 1 are printed on the front face of the paper table 26 adjacent the right hand edge of the table for indicating the three positions of the unlatching bar and its operating handle.

Mounted on the margin stop bar 19 are the two adjustably settable margin stops L and R slidably adjustable independently along the stop bar and 20 releasably latchable to said bar in different letter space positions for determining the left and right hand margins of the writing to be done by the machine upon a work sheet. As the two stops are of generally similar construction, except as hereinafter explained to adapt them for use as left and right hand stops, the general structure of the stops will be described using like reference characters for like parts of the two stops L and R.

Each stop (L or R) comprises a stop body 30 slideable along bar 19 and consisting of parallel flat top and bottom walls 41 and 42 joined by a flat rear wall 43 integral with the top and bottom walls, and a detachable flat front wall 44 detachably held to the front edge of the bottom wall by 35 screws 45, the four flat walls defining a rectangular stop body having a passage of oblong cross-section therethrough from the right to the left side of each stop, which passage is just large enough to slidably receive the toothed stop bar 40 19—19^a, as will be apparent from Fig. 7 for example. Said passage conforms substantially in cross-section to the cross-sectional contour of bar 19—19^a.

Each margin stop L or R also includes a releasable stop detent or latch plunger device for 45 latching the stop to the bar 19 in any selected letter space position along the bar, it being understood that the teeth 19^a of bar 19 are uniformly spaced apart a distance equal to one letter space 50 movement of the carriage 11 under control of its escapement device as is usual in the art.

Each detent device D comprises an upper operating head and a lower latching head rigidly connected by a stem to which the heads are 55 rigidly fixed. The stem and its rigidly united latching head of each stop are generally similar to the corresponding parts of the adjustable margin stops of the prior patent above referred to and need therefore to be only briefly described. 60 The latching head consists of two parallel teeth 46 underlying the stop bar and spaced apart two letter space distances longitudinally of bar 19 and integrally joined at their rear ends by a connecting bar 47, said head being guided to move perpendicularly of the stop (edgewise of bar 19) in a slot 48 formed in the rear end bottom walls 43 and 42 of the stop body. The stem 49 is cylindrical and rises from the latching head slightly 70 forward of the rear edge of the tooth connecting bar 47, said stem being partly countersunk in a vertical groove 50 in the front face of the rear wall 43 of the stop body, the stem being guided in a circular aperture 51 in the top wall 41 of the stop body and projecting above said wall. The

stem is reduced within the stop body upward from the latching head to provide a flat face 52 thereof flush with the front face of the rear wall of the stop body and to provide a downwardly facing shoulder overhanging the upper edge of the stop bar 19. At its upper end, and spaced above the stop body, the stem 49 is formed with a reduced and, preferably, flattened upper end portion 53 to which is fixed (at the lower end of said reduced end portion 53) the operating head of the 10 detent device D.

The operating head of the detent device D of each margin stop includes an antifriction roller 55 and a head element 56 to which element and to the reduced upper end 53 of the stem 49 the roller 55 is rotatably held, the element 56 being formed of a single piece of stiff sheet metal permanently bent to partially surround the stop releasing or unlatching bar 31. In the construction shown the head element 56 consists of a sheet metal strap or bar permanently bent laterally to form a bottom wall, a front wall, a top wall, and a rear wall which extends only part way upward from the bottom wall toward the rear edge of the top wall. The opening between the rear and top walls is wide enough for passage of bar 31 therethrough to facilitate assembly of the parts. The bar 31 is rockable to its full extent of oscillation within the head elements 56 without colliding with the walls of said elements. In the latched position of the margin stop with teeth 46 fully seated or meshed with teeth 19a of bar 19, the bar 31 does not contact either the roller 55 or the top wall or any other part of the head element, as will be apparent from Figs. 2 and 7 for example. To insure this, the stop arms 34 and 35 for bar 31 are adjustably bendable as hereinbefore described. Roller 55 of each stop L or R is revolute about an axle 57 fixedly held to head element 56 and stem portion 53, said axle and roller extending fore and aft of the machine perpendicular to the planes of the front and rear faces of margin stop bar 19. The detent device D of each stop is normally forced up to latched position by a return spring 61 coiled about stem 49 between the bottom wall of head 56 and top wall 41 of the stop body.

In the case of the left hand margin stop L the roller axle 57 is held to reduced stem part 53 and the rear wall of the head element 56, and roller 55 underlies the rear pendent flange of unlatching bar 31. Fixedly held to or formed on the rear wall 43 of the stop body of this stop is the usual abutment element or rearwardly extending projection 58 for abutting frame stop element 17 to arrest return movement of the carriage.

In the case of the right hand margin stop R roller axle 57 is held to reduced stem part 53 and the front wall of head element 56, the roller 55 of this stop underlying the front pendent flange of unlatching bar 31. Fixedly held to or formed on the rear wall 43 of the stop body of this stop is the usual rearwardly extending abutment element 59 for abutting frame stop element 18 to arrest letter feed travel of the carriage from right to left in typing a line, said rear wall 43 also having fixedly held thereto the usual alarm bell actuating projection 60.

Either of the stops L and R may be released and adjusted along the stop bar and re-latched to said bar in a desired different letter space determining position by direct hand manipulation after swinging of the hinged upper section of paper table 26 forward to uncover the stops and 75

stop bar which are normally covered by the proper table (see Fig. 2). To thus re-set either stop directly by hand it is simply necessary to press down on the top wall of the head element 56 of the stop detent or latch D with a finger of one hand, then move the finger in the necessary direction longitudinally of the bar until the desired position is reached by the unlatched stop and then release the stop latch D which will then rise under the influence of its return spring 61 and latch the stop. A small aperture 73, smaller than the finger size may be provided in the top wall of element 56 to facilitate lateral direct hand shifting of the stop.

Resiliently controlled tension means are provided for automatically drawing either of the stops L and R toward the other and toward its coactive counter stop element on the machine frame when the stop is unlatched from the stop bar, the stop elements 17 and 18 on the frame being located between the margin stops. This automatic power drive of a released margin stop is effected in the construction shown by a small spring drum 62 and drum cable or cord 63. Said drum is journaled on a stub shaft 64 fixedly held to and projecting forward from the front wall 44 of the stop body of the right hand margin stop R, the drum being held on the shaft by a nut 65 threaded on the shaft. A spiral spring 66 anchored to the stationary stub shaft and to the peripheral wall of the drum constantly tends to rotate the drum clockwise as viewed in Fig. 1 and wind up the cable 63 upon the drum. The cable is anchored at one end to the drum and passes from right to left over the top of the drum, and thence under a small idle guide pulley 67 on stop R to the stop L where it is tied or otherwise anchored to a stud 68 projecting forward from the front wall 44 of the body of stop L. Pulley 67 is journaled on a small stub shaft 69 projecting forward from and rigidly fixed to front wall 44 of the body of stop R.

From the foregoing it will be observed that to reset the left hand margin stop for a wider margin it is simply necessary to move the carriage to the desired letter space position, then rock handle arm 37 from its intermediate normal position (indicated by the indicium "Lock" on the paper table) upward and rearward to the position indicated by the indicium "L.set" and hold it there with stop 35 engaged against bar 19 until the spring drum and cable drives stop L rightward along bar 19 up against stop 17 on the frame, and then release the handle arm which will thereupon be restored to "Lock" position by spring 38. To re-set stop L for a narrower margin it is released and held released by a similar movement of handle arm 37 to "L.set" position and held released while the carriage is moved rightward to the desired letter space position for the new margin with stop L engaged with stop 17 thus shifting stop L leftward along the bar. Upon release of handle arm 37 the stop L will be latched in its new position.

65 To re-set the right hand stop R for a wider margin the carriage is moved into the proper letter space position and arm 37 is rocked downward and forward to the "R.set" position and is held there with stop 34 abutting bar 19 while the spring drum and cable act to drive stop R along bar 19 toward the left up against stop 18, whereupon the stop may become latched in its new position by release of arm 37 which will then be restored by spring 38 to "Lock" position. To re-set stop R for a narrower margin the stop is re-

leased and held released as above described while the carriage is moved leftward to the desired letter space position with stop R engaged with stop 18 to thereby shift stop R rightward along the bar, and the stop is then latched by releasing arm 37.

It will be observed that in all positions of the release bar 31 there is no contact between said bar and any part of the head element 56 of either stop L or R. It will also be observed that, while either stop L or R is released, the sole contact between the released stop and the release bar 31 is between the lower edge of one pendent flange of bar 31 and the antifriction roller 55 of the detent device D of the released stop. It will be observed that in the normal position of the release bar 31 there is no contact between the release bar and any part of either of the stops L or R including the roller 55 and the head element 56 of each of said stops. The limits of stop-releasing rocking movements of bar 31 are such that at each such limit the latch device D of the released stop is depressed just far enough for free clearance of teeth 46 from the teeth of bar 19, and, preferably, also that the downwardly facing shoulder on stem 49 overhanging the stop bar 19 does not contact the bar 19. Preferably, also, the top edge of bar 19 is rounded or convex transversely of the bar as shown. There is, therefore, a minimum of resistance to sliding of either stop L or R along the bar 19 upon release of the stop. It is thus possible to employ a very small, light and inexpensive spring drum 62 without any danger of failure of the released stop to slide to its new position.

The construction of the head element 56 of the detent device D of each stop L or R is such as to contribute to lightness and low cost of the stop as well as to permit either direct hand setting or indirect hand-controlled setting of each stop. The channel sheet metal construction of release bar 31 provides a very light bar which is nevertheless highly resistant to sagging or bending.

The features of construction pointed out to eliminate friction, reduce expense and size and weight, and provide a compact assembly, are highly important in mechanisms of the character to which the invention relates, and it is highly desirable in such mechanisms to not only keep down cost but to so construct the mechanism that it be light and compact yet both sturdy in construction and certain in its operation.

Certainty of operation is exceptionally important in a mechanism for indirect, hand-controlled, semi-automatic stop setting, as in such mechanism it is usually impossible for the operator to see the stops and tell before trial whether or not the stops are correctly set. In such mechanisms a difficulty arises with respect to correct setting and latching of the settable left hand margin determining stop. Means are provided by the present invention in connection with the left hand margin stop L to overcome this difficulty, and said means will now be described.

It is usual, if not in fact absolutely essential, in returning the platen carriage of a typewriting machine, after letter feed thereof by an escapement, that the usual abutment (such as 58) on the left hand settable margin stop (such as stop L) shall not contact its coactive abutment (such as 17) on the machine frame to stop the return of the carriage until the carriage

has moved rightward in return direction a fraction of one letter space distance beyond the true letter space position of the carriage for the left hand margin of the writing, from which 5 "false" or maximum return position the carriage is pulled back to the "true" position by the action of the usual spring drum of the escapement mechanism which urges the carriage leftward. This overthrow return is required in order to insure the passage of the proper tooth of the escapement rack or wheel past the normally engaged dog of the escapement.

According to the construction shown, there is provided in the left hand margin stop L for 10 overcoming the aforesaid difficulty an auxiliary up-and-down shiftable abutment 10 in the form of a sheet metal finger rigidly held at its upper end to the rear wall of head element 56 of the detent device D of said stop by the axle element 20 57 for the roller 55 of said detent device. The element 57 clamps the upper end of abutment finger or slide 10 to said wall of head element 56, and said finger 10 is held against swinging about element 57 by lugs 71 on said finger which 25 are bent around the vertical side edges of the rear wall of head element 56. The finger 10 is held to slide up and down with its straight left hand edge against the abutment face of abutment portion 58 of stop L as shown and has 30 a reduced lower end portion the width of which longitudinally of the stop bar 19 and transversely of the machine is less than the distance of one letter space travel of the carriage and equal to the extent of said normal overthrow. 35 The reduced lower end portion of finger 10 is normally held up by the detent device D high enough (as shown) to clear abutment 17 on the machine frame, but when detent device D is pressed down to stop releasing position the 40 finger 10 moves down with it just far enough to interpose its said reduced lower end portion between abutment 58 and abutment 17 so that the released stop L will engage abutment 17 through the medium of the auxiliary abutment or finger 10. Stop L will therefore be stopped by stop 17 in proper position for latching of the stop L to bar 19 upon release of handle arm 37 in a stop setting operation for said stop L. When the detent device D of said stop moves 45 into latched engagement with the teeth of bar 19 on release of handle arm 37, the auxiliary abutment 10 rises to normal position and the carriage stays in true letter space position with the usual fractional letter space separation of 50 abutments 17 and 58 until the carriage is fed leftward in typing the line.

The modified embodiment of the invention shown in Figs. 13 and 14 adapted for wide carriage machines will now be described. The several parts of the modified form of machine including the stops and their setting means, and the mode of setting the stops, are the same as in the construction above described except as hereinafter pointed out. Like reference characters are therefore employed to designate like parts and to simplify and condense the description necessary to understand the modified embodiment.

In the modified construction the platen carriage 11 is approximately twice as wide transversely of the machine as the carriage in the construction of Figs. 1 to 12 and approximately twice as wide as the main frame 10 of the machine. Such a wide carriage (or still wider carriage) obviously requires the use of a correspond-

ingly long unlatching or releasing bar for the stops L and R, and also a correspondingly long margin stop bar 19. Such exceptionally long bars may sag or bend between their ends.

To prevent danger of this sagging or bending of the unlatching bar in the modified construction said bar comprises two channel sections 31^a and 31^b each similar to bar 31 in the construction of Figs. 1 to 12, and this duplex bar is braced and rockably supported on the carriage substantially midway its ends and mid-width of the carriage. The adjacent ends of sections 31^a and 31^b have riveted in the channels thereof (as indicated at 72 in Fig. 14) lateral extensions 14 of the side arms of a small and rigid metallic connecting yoke 15. The left hand side arm of yoke 15 has rigidly fixed thereto a trunnion 16 which is coaxial with the two outer end trunnions 33^a and is journaled in a bearing hole in a sheet metal bearing bracket 11. The bearing hole in bracket 11 is coaxial with those in brackets 30. Bracket 11 is rigidly held by a screw 18 to the upper end of a bracket 19. Bracket 19 is held at its lower end to the carriage 11 by screws 80 and is located substantially midway between the ends of the carriage.

The brackets 19 and 11 thus support and brace the stop releasing bar, and bracket 19 also supports and braces the long dentated margin stop bar 19 of the modified machine, said bar 19 being clamped midway between its ends to the rear face of bracket 19 by a shouldered screw 81 tapped rearwardly through the bracket.

The cable 63 attached to spring drum 62 carried by the right hand margin stop R is, in the modified construction, tied or otherwise anchored to the protruding forward end of the shouldered screw 81 instead of being tied or anchored to stop L. In the modified construction a spring drum 62^a similar to drum 62 is similarly journaled on the front wall 44 of the body of stop L, and the cable 63^a of this drum 62^a passes rightward from the lower part of the drum over an idle guide pulley 67^a (similar to pulley 67) and is also tied or anchored to the forwardly protruding end of screw 81. Pulley 67^a is journaled on the front wall 44 of the body of stop L in the same manner that pulley 67 is journaled on stop R. The spring of drum 62^a constantly tends to turn said drum clockwise as viewed in Fig. 13 and wind cable 63^a on said drum, as is the case with drum 62. By employing two spring drums with their cables as shown and described very small and inexpensive drums can be used in connection with wide carriages having a very long range of travel.

What I claim is:

1. In a typewriting machine of the kind having a main frame and an extra wide platen carriage mounted on the main frame to travel back and forth transversely of the machine, the combination with said main frame and extra wide carriage of margin regulating means comprising, in combination, a dentated margin stop carrying bar fixedly supported on the carriage at its ends adjacent opposite ends of the wide carriage, a manually-shiftable spring-returned margin stop releasing device extending substantially from end to end of the extra wide device extending substantially from end to end of the extra wide carriage and oppositely shiftable from an idler spring-returned position to either of two margin stop releasing positions, means on the extra wide carriage substantially midway between the ends of the carriage rigidly supporting the stop bar

and also supporting the releasing device for shifting of the latter, means shiftably supporting said releasing device adjacent opposite ends of the wide carriage, left and right hand adjustably settable margin stops, releasable self-latchable means carried by each of said stops to latch said stops to said bar, said stops being mounted on said bar for sliding adjustment therewith into different set and locked positions with respect to said bar, said releasing device being operable upon different ones of said latching means of said margin stops when shifted in different directions from its idle position for selectively releasing the margin stops, motor means for driving the released stop toward the other stop upon release of either stop, and counter stop means on the machine frame intermediate the settable margin stops for coaction with the settable margin stops to determine the left and right hand margins of matter typed by the machine.

2. In a typewriting machine of the wide carriage variety as claimed in claim 1, the self-latchable means of the left and right hand margin stops being each provided with an antifriction roller engageable by said oppositely shiftable releasing device to unlatch the stop and hold it unlatched during driving thereof by the motor means.

3. In a typewriting machine of the wide carriage variety as claimed in claim 1, the self-latchable means of the left and right hand margin stops being each provided with an antifriction roller engageable by said oppositely shiftable releasing device to unlatch the stop and hold it unlatched during driving thereof by the motor means, and each of said self-latchable means being also provided with a finger piece directly operable by hand to unlatch the stop and hold it unlatched during sliding direct hand adjustment of the released stop along the stop bar.

4. In a typewriting or like machine, a margin regulating means comprising, in combination, a margin stop carrying bar, left and right hand margin stops mounted on said bar and adjustably slidably therealong and each including releasable means for locking the stop to the bar in desired adjusted position, a single sheet metal releasing bar for the pair of margin stops, said bar being of channel form in cross section and extending longitudinally of the stop bar, means supporting the releasing bar for opposite rocking thereof about an axis extending longitudinally of the bars, a handle for rocking the releasing bar, an antifriction roller carried by the locking means of each stop for releasing of the stop by pressure of the longitudinal edge of one flange of said releasing bar on the periphery of said roller, the rollers extending transversely of the releasing bar and being arranged for engagement of the periphery of each thereof by a different flange of said releasing bar, spring means for returning said releasing bar to and normally holding it in an intermediate idle position in which both margin stops are locked to the stop bar, counter stop means for the margin stops, said bars and margin stops being mounted for relative travel between the same and said counter stop means longitudinally of the bars with the counter stop means located intermediate the two margin stops, and automatically operating means to slidably move along the stop bar toward the counter stop means that one of the margin stops which is released by rocking of the releasing bar from the normal position of the latter.

5. A typewriting machine of the kind having

a main frame and a platen carriage mounted on the main frame to travel back and forth transversely of the machine, wherein is provided margin regulating means comprising, in combination, a margin stop carrying bar fixedly mounted on the carriage adjacent opposite ends of the bar and carriage, means on the carriage substantially midway between the ends of the bar and carriage fixedly supporting said bar, left and right hand margin stops adjustably slidable on the bar longitudinally of the bar and each including a locking means normally releasably locking the stop to the bar in adjusted position, a single oppositely shiftable releasing means for said margin stops extending longitudinally of said bar and supported on the carriage adjacent opposite ends of the carriage and also supported by said bar supporting means located midway between the ends of the carriage, said releasing means being normally spring held in an intermediate idle position and being operable by hand to act upon the locking means of different ones of the margin stops to unlock the stop and hold it unlocked throughout the field of adjustment of the stop when said device is shifted in different directions from its idle position, a spring drum of each margin stop, two cables each connected to a different one of said drums and to said central supporting means for the stop bar and releasing means for constantly urging the two stops toward each other, and counter stop means for the margin stops mounted on the main frame between said stops.

6. A typewriting machine as claimed in claim 5, wherein the locking means of each margin stop includes a finger piece directly operable by hand to release the locking means of the stop and antifriction means carried by the locking means and engageable by said oppositely shiftable hand operable means to release the stop, and said last-mentioned means extends longitudinally of the carriage between the finger piece and said antifriction means.

7. A typewriting machine of the kind having a margin stop supporting means, a pair of margin stops mounted on and independently adjustable along said supporting means and each including releasable locking means normally effective to lock the stop to its supporting means in a selected margin determining position, and counter stop means for said margin stops mounted therebetween for relative back and forth travel between the counter stop means and the margin stop supporting means parallel to the typing line of the machine, wherein the said releasable locking means of each margin stop is provided with an antifriction roller shiftable by pressure on its periphery to shift the locking means to unlock the margin stop, a hand rockable stop-releasing bar of channel cross section extends longitudinally of the margin stop supporting means and typing line of the machine in non-traveling relation to the margin stop supporting means and has its opposite side walls disposed for pressing engagement with the antifriction rollers of different margin stops when said bar is rocked in different directions, and means is provided for restoring said bar to an intermediate idle position in which both margin stops are held locked by their locking means.

8. A typewriting machine as claimed in claim 7, wherein the releasable locking means for each margin stop has a finger piece for direct hand unlocking of the stop by direct hand pressure on the finger piece, and said stop releasing bar ex-

tends between the finger piece and antifriction roller of each stop.

9. In a typewriting machine having a main frame and an escapement controlled carriage 5 movable back and forth transversely of the main frame, margin regulating means comprising, in combination, a dentated margin stop bar traveling with the carriage, a left hand margin stop mounted on said bar for adjustment therealong and including a shiftable detent device shiftable 10 to unlock the stop from the bar for adjustment of the stop, and counter stop means on the main frame for said left hand margin stop, said margin stop having a main abutment engageable with said counter stop means in all locked adjusted positions of the stop and an auxiliary abutment shiftable with said detent device to engage said counter stop means only while said detent device is in stop unlocking position, said 15 auxiliary abutment being arranged to engage the counter stop means, when said auxiliary abutment is rendered effective, at a point a fraction of one letter space distance of travel of the carriage in advance of the point at which said main abutment would otherwise engage the counter stop means.

10. In a typewriting machine having a main frame and an escapement-controlled traveling carriage reciprocable relatively to the main 30 frame for letter-spacing and return movements of the carriage, margin-regulating means for determining the limit of return movement of the carriage comprising, in combination, a dentated margin stop carrying bar extending parallel to 35 the path of travel of the carriage, a margin stop slidably adjustable along said bar, means carried by the said margin stop to releasably latch said stop to said bar at different letter-space intervals, counter-stop means engageable by said margin stop to arrest return movements of the carriage, said bar and counter-stop means being mounted for relative travel therebetween in the direction of the length of the bar during carriage travel, and normally ineffective means shiftable with the releasable latching means carried by said margin stop and automatically positioned by release of said latching means for engagement with the counter-stop means upon 40 relative sliding movement between the bar and margin stop to locate the margin stop for relatching of the latter to the bar in position for coaction of the margin stop with the counter-stop means, during subsequent return movement of the carriage, to arrest the carriage.

11. In a typewriting or like printing machine having a main frame and a paper carriage which is movable back and forth parallel to the printing line of the machine for letter-space feeding movement and return movement and is escapement-fed in letter-space feeding direction, a margin stop bar extending parallel to the path of movement of said carriage, a margin stop slidably adjustable along said bar and including means for normally releasably locking the margin stop to the bar in any selected one of a plurality of positions spaced apart at letter-space intervals along said bar, counter-stop means for said margin stop, said bar and counter-stop means being mounted for relative travel in the 50 direction of the length of said bar during feed and return movements of the carriage, and means carried by the margin stop for contact with the counter-stop means and comprising two abutments one of which is movable with the releasable locking means to place it in position for

contact with said counter-stop means while the margin stop is released from said bar and movable out of position for contact with the counter-stop means when the margin stop is locked to said bar, the other abutment being arranged for contact with the counter-stop means while the margin stop is locked to the bar, the two abutments being relatively arranged to contact the counter-stop means at two points spaced apart, relatively to said margin stop, a fraction of one letter-space distance of travel of the carriage.

12. In a typewriting or like printing machine having a main frame and a paper carriage which is movable back and forth parallel to the printing line of the machine for letter-space feeding movement and return movement and is escapement-fed in letter-space feeding direction, a margin stop bar extending parallel to the path of movement of said carriage, a margin stop slidably adjustable along said bar and including means for normally releasably locking the margin stop to the bar in any selected one of a plurality of positions spaced apart at letter-space intervals along said bar, and counter-stop means for said margin stop, said bar and counter-stop means being mounted for relative travel therebetween in the direction of the length of said bar during feed and return movements of the carriage, said margin stop having two relatively shiftable abutments one positioned to engage the counter-stop means while the stop is locked to the bar and the other shiftable with the margin stop locking means into position to engage the counter-stop means while the stop is released from the bar and shiftable out of said position when the margin stop is locked to the bar, the latter abutment being located a fraction of one letter-space in advance of the former abutment with respect to the direction of return movement of the carriage.

13. A typewriting or like printing machine of the kind having a main frame and a paper carriage which is movable back and forth in a path parallel to the printing line of the machine and is escapement-fed in one direction of its travel for letter spacing, characterized in that said machine is provided with margin-determining means comprising, a dentated margin stop bar held to the carriage, a carriage return limiting margin stop slidably adjustable along said bar and including releasable latching means normally engageable with teeth of said bar to latch said stop to said bar at any selected one of a plurality of letter-space intervals along the bar, counter-stop means on the main frame for said margin stop, means on the carriage independent of said margin

stop operable to release said stop latching means and hold it released throughout the field of adjustment of said stop, and means constantly tending to urge said stop toward said counter-stop means, said stop having two abutments for engaging said counter-stop means, one of said abutments being shiftable with the margin stop latching means into position to engage said counter-stop means only while the stop is released and being, when so positioned, interposed between the other abutment and the counter-stop means and a fraction of one letter-space distance nearer the counter-stop means than said other abutment.

14. A typewriting or like printing machine of the kind having a main frame and a paper carriage which is movable back and forth in a path parallel to the printing line of the carriage and is escapement-fed in one direction of its travel for letter spacing, characterized in that said machine is provided with margin-determining means comprising, in combination, a dentated margin stop bar held to the carriage to travel therewith and extending parallel to the path of carriage travel, a carriage feed limiting margin stop and a carriage return limiting margin stop slidably adjustable along said bar and each including releasable latching means engageable with teeth of said dentated bar for latching it to the bar at selected intervals spaced letter-space distances apart along the bar, counter-stop means for each margin stop mounted on the machine frame, means mounted on the carriage operable to selectively release the latching means of the margin stops and hold the released latching means released throughout the field of adjustment of the released stop, and means constantly tending to urge the margin stops toward the counter-stop means, said carriage return limiting margin stop having an abutment engageable with the counter-stop means for said stop, said carriage feed limiting stop having an abutment for engaging the counter-stop means for said stop, and said carriage return limiting stop alone of said two margin stops having a normally ineffective supplemental abutment shiftable with the latching means for said stop and positioned by release of said latching means to engage the counter-stop means for said stop, the supplemental abutment being engageable with the counter-stop means to hold the other abutment of the carriage return limiting margin stop a fraction of one letter space away from the counter-stop means.
